STATIC REFRIGERATING PLANT

Filed Dec. 4, 1929

UNITED STATES PATENT OFFICE

MARCELINO CARRANZA, OF BUENOS AIRES, ARGENTINA

STATIC REFRIGERATING PLANT

Application filed December 4, 1929, Serial No. 411,573, and in Argentina November 12, 1929.

My invention relates to statical refrigeration, and more especially to refrigerating devices involving two receivers having spherical or cylindrical form, both being connected by a pipe, in which is contained the refrigerating liquid. In the use of devices of this kind for heating purposes and also for cooling purposes, an intense coldness is produced under very economical conditions but with 10 serious inconvenience of handling and considerable effort in the manipulation results for the required purposes.

In order that this type of refrigerating device heretofore mentioned should develop 15 cold, reference being had to the accompanying drawing, the following manipulations are necessary:

First manipulation.—The device should be bodily lifted out of the refrigerator, the 20 point A of the outer sphere A resting on the floor, and sphere E remaining elevated. In this position all the liquid that may be contained in E passes in five minutes to A. This time can be reduced by covering the receiver 25 E with a cloth soaked in hot-water or pouring on E a small quantity of hot-water. The liquid runs rapidly through the pipe C and is deposited in its entirety in the sphere A; this being done, the:

Second manipulation, which is the hardest, is as follows: The device should be taken to a receiver containing fresh-water, part E being placed in the water and part A remaining outside of the receiver. Under A is 30 placed a fire whether emanating from kerosene, gas, electricity, etc. During the space of one hour and a half heating is effected, and at the end of this period all the liquid contained in A will pass to E, internal evaporation having ceased, the heat in the cupola B, which has previously been filled with water, automatically increases, steam is emitted and the whistle F gives warning that the operation is or rather will be terminated in about

10 to 20 minutes. Once this is finished, there should be proceeded with:

The third manipulation.—The device is lifted and placed in an inverse position, that is to say: part E outside of the receiver and part A in the water. In doing so, the steam in the cupola B is condensed and absorbs water from the receiver, thus remaining filled for the next operation: an interval of five minutes should be allowed to elapse before carrying out the:

Fourth manipulation.—The spheres should be lifted and taken back to the refrigerating chest, and thereafter is effected the:

Fifth manipulation.—The spheres should be lifted in order to be placed in the refrigerating chest through its top part. This being done an intense cold is developed immediately, and at a cost less than \$0.10 m/l there is obtained a very good and dry refrigeration during a period of 36 hours.

As may be observed, all this requires a great deal of work and effort, but acceptable by virtue of the infinitely low cost; on the other hand it is objectionable by reason of the manipulations indicated on account of the excessive weight, impracticable for servants and house-owners. It always happens that ice-chests are placed in a position near to the dining-room, that is to say, in the centre of the house, but the receiver in which the spheres will have to be submerged, which must be cube of considerable size, the handling of kerosene, water that is spilled on putting in and submerging the spheres, besides the odor from the combustible, debars such an operation from being put into practice in the centre of the house where the receiver for the immersion would have to be installed. For such reason, the receiver in question should be placed at the back of the house and the work carried out in a room, since the wind will put out or affect the action of the lamp or gas.

From the centre to the back of a house there

is a distance approximately of about 30 or 40 metres, and there may or may not be a room suitable for the manipulations and of hygienic conditions.

- 5 Taking modern apartments as an example, the matter becomes complicated by reason of the fact that there is a shortage of space; and in the case of a petit-hotel, the spheres will have to be taken to the ground or top floor, 10 from all of which it results that notwithstanding its great economical working it is unacceptable, excepting in the country in general where ample room is available and transportation easier.
- 15 The present invention aims to eliminate the inconveniences and the foregoing manipulations, excepting to apply water without any perceptible effort, in the use of the devices for refrigeration.
- 20 In the accompanying drawing the view is a fragmentary vertical sectional elevation of an ice chest constructed in accordance with the invention, the refrigerating device being positioned therein.
- 25 Referring to the drawing in detail, the two spheres A and E are joined by the pipe C and the welded shaft D. On the sphere A is welded a cupola B, which is provided with a blower F; at the left of this is a screw 30 regulator for the blower and further to the left a cover for filling water in the steam cupola B before commencing to operate. Two small safety valves are welded on the part E, there being only one visible in the drawing.
- 35 Another safety valve is welded on A at the back of the same, this valve also being not visible in the drawing.

In the side of an ice-chest an opening is made, preferably somewhat larger than the 40 diameter of the sphere E of the refrigerating device and of a height in relation thereto beyond its uppermost point, while hinges are fitted at the point C of this opening to 45 swingingly support a door that operates in a vertical path, as shown in the drawing by the arrow H, the door being normally retained in a vertical position by means of a suitable latch. On this door is placed the receivers or spheres A and E of the device, 50 thus forming a part of the ice-chest. The part of the pipe C connecting the receivers that remains in the ice-chest is concentrically lined with inoxidizable plate, leaving a small space between the plate and the pipe. On facing 55 the sphere the plate-covered pipe opens, reaching the sphere itself and fastening it as per I, J. The parts K and L should be duly covered in order to avoid the escape of water that will circulate in the space between the 60 pipe and the plate. Near to the part L, a hole of small diameter is drilled for the escape of impurities and for the outlet of the water, which on the completion of the operation should be allowed to entirely drain off, since 65 on freezing it will result in breakage of the

plate or unsoldering of same. At the extreme left of the part covered at L there is an arm that supports a sprinkler with fine holes for sprinkling the larger part of E, thereafter running through the sphere. If the sprinkler does not give a good distribution of water in an homogeneous manner, there will have to be fitted thereon a cowl not shown of ordinary thick cloth (a floor-cloth which will serve the purpose well).

70 N is a pipe which conducts the water after it has passed through the dismountable filter N, and the pipe O in which is placed at will a water-cock or nipple for adjusting a rubber pipe. Around the steam cupola B is soldered a metal hoop P, perforated with a number of small holes around the part soldered to the cupola.

80 Underneath pipe C is soldered a small pipe Q from which branches off another of smaller diameter, on which is fitted another water-cock or nipple adjuster. The position indicated in the drawing for these pipes has been elected with a view to the maximum visibility, but in practice this may be arranged in 85 the manner most convenient.

90 Under the sphere E is the receiver R constituting a stabilizer for the water emanating from E. A drain-pipe S is fitted to this receiver and terminating at the upper end 95 T in a plug of insulating material with holes or openings inclined towards the top, which serves as a siphon while the pipe S below the siphon conducts the water through U outside.

100 The siphon formed by the insulating plug has for its object that once the circulation of water is terminated, freezing takes place therein which automatically avoids the outlet of cold produced at the base of K.

105 On the pipe U is fitted a font X of convenient width, depth and height, in order to allow the coupling therewith of a circular tray V of a diameter somewhat greater than A, with a lip extending into X that fastens on the side of the tray, the member Y is provided and supports the tray V, the latter being slightly inclined, to discharge the water in the trough as indicated by the arrow in the drawing. The said small trough can take the 110 shape of a funnel and is fixed to the ice-chest. The tray V can also be supported by a horizontal pipe (which serves for draining off) soldered to a revolving body fixed in the ice-chest and communicating with pipe U, thus avoiding the necessity of the labour of fitting and taking off the tray, reducing the manipulation of turning it to make room for the lamp or source of heating and inversely placing it under A to receive the water.

115 In Z is fitted an insulating fan, in order to avoid producing calefaction, the heat is transmitted to the ice-chest. Everything being arranged as indicated, below is given the 120

form in which it is proposed to eliminate the five manipulations hereinbefore described.

The tray V is removed and drawing back the latch that maintains the movable part of the ice-chest in a vertical position, turn it in the direction indicated by the arrow H, until the part A touches the floor. In this position the part E is elevated and is at the highest point; the draining of the interior liquid is effected without the necessity of having to lift a weight of 18 kilos or more. The draining can be facilitated by a cloth steeped in hot-water in order not to cause leakings. Having effected the draining, the device is again lifted, the water-cock is shifted and will remain in a vertical position, and latched. heat is applied below sphere A, and the current of water passes through O, which on arriving at C impedes the transmission of heat from C to the ice-chest. The water falls to L and later goes out through K to the sprinkler M, bathes the sphere direct or through the medium of the cowl made of cloth or fabric, and facilitates in E the condensation of the ammonia liquid. The water falls later onto the stabilizer, escapes through S without allowing the frigidity produced to escape later, and without the least heat which it transports, being transmitted to the stabilizer from which it is isolated.

This operation should last an hour and a half, with the water constantly in circulation and of sufficient quantity; a quick refrigeration is effected, much quicker than that obtained previously by immersion in a vat of water, because the temperature of this latter rises much more appreciably, thus retarding condensation and diminishing the effectiveness of the mechanism.

The evaporation having terminated in A, the temperature continues to rise. The water contained in B commences to boil and the steam generated escapes by the whistle announcing the fact that the operation will be completed in a few minutes' time.

At the end of this period the current of water through O is cut off and it is initiated in Q. The water arriving produces the condensation of the steam in B, the vacuum absorbs the water, filling B for the next operation. The water continues running and overflows in the space limited by the crown and escapes through the holes made at the base thereof, bathing and cooling at A, falling later on in the small tray V, from there to the small trough and to the drainage U.

A having undergone this operation for five minutes, the water is cut off and freezing commences to be developed in the sphere E, causing a drop in the temperature of 19 to 20° centigrade in the course of an hour.

All that has been previously described has occurred without the operator suffering any inconvenience, the operations being effected

in less time than under the manipulation heretofore.

As will be seen, the voluminous refrigerating vat is dispensed with and the numerous manipulations avoided, with the consequent danger of damage to the woodwork of the house and to the spheres or cylinders themselves. 70

With this procedure is also removed the risk of servants applying heat to the sphere E instead of A, which will immediately cause the deterioration of the refrigerator. 75

There can be eliminated the small trough, the tray V, the crown P and the pipe Q destined for the refrigeration of A; in this case 80 it would be sufficient to place below A, a bucket of proper dimensions, containing water, and at the moment of effecting the refrigeration of A it should be raised until the whistle is submerged. This would simplify the 85 structure, but on the other hand an inconvenience is introduced and more effort is added to the operation.

The steam cupola may be dispensed with and to effect the calefaction with a naphtha or kerosene lamp, filled with a quantity of combustible equal to that which may be consumed during the period of one and a half hours. At the expiration of this period, the lamp is extinguished by itself since the operation is completed, but without any indication that such is the case; this, however, can be done by a procedure which will be the subject of another patent, it being sufficient for the present to utilize an alarm clock 100 whose bell will sound an alarm one hour and a half after the commencement of the calefaction. 95

The improvement described can be applied to existing ice-chests, provided an opening 105 is made in the ice-chest, but in the event it is not possible to carry out this work in the country, the improvement can be limited to the spheres only conveying them to the distributor. Refrigeration can be effected with 110 them, one effort only being necessary, that is to say, that required for lifting them, taking them out and placing them in a draining position and to again fit them to the ice-chest and proceed with the calefaction and 115 circulation of water, avoiding the transportation of the refrigerating vat, i. e. the trip to the back of the house.

Resuming: There is a saving in effort, 120 spilling of water is avoided, the refrigerating vat is eliminated, transportation and deterioration through knocking about are excluded, time is economized, and a more efficacious refrigeration is obtained, all of which have been demonstrated on numerous occasions. 125

The use of this type of refrigeration device is simplified in such a manner that it can compete with advantage with electric ice-chests, which latter while not requiring 130

any attention, are susceptible to breakdowns, the cost of acquisition of which is much greater, and its daily consumption in material very high.

5 Having thus described the nature of my invention and the manner in which it should be put into practice, I hereby declare that I claim as my exclusive right:

1. The combination of an ice chest having an opening, a swinging closure therefor movable in a vertical path, and rocking refrigerating means carried directly by and operative on movement of the closure with one part within and another part without the

15 chest and the within part movable through the opening for the closure.

2. The combination of an ice chest having an opening, a swinging closure therefor movable in a vertical path, rocking refrigerating

20 means carried by and operative on movement of the closure with one part normally within and another part without the chest and the within part movable through the opening for the closure, and a cooling liquid lead between the parts.

25 3. The combination of an ice chest having an opening, a swinging closure therefor movable in a vertical path, rocking refrigerating means carried by and operative on movement

30 of the closure with one part within and another part without the chest and the within part movable through the opening for the closure, a liquid lead between the parts, and means for circulating liquid about the part normally within the chest.

35 4. The combination of an ice chest having an opening, a swinging closure therefor movable in a vertical path, rocking refrigerating means carried by and movable with the clos-

40 ure with one part normally within and another part without the chest and the within part movable through the opening for the closure, a cooling liquid lead between the parts, means for circulating liquid about the part normally within the chest, and a temperature stabilizer within the chest and having escape without the same.

45 5. The combination of an ice chest having an opening, a swinging closure therefor movable in a vertical path, rocking refrigerating means carried by and movable with the clos-

50 ure with one part normally within and another part without the chest and the within part movable through the opening for the closure, a cooling liquid lead between the parts, means for circulating liquid about the part normally within the chest, and a temperature stabilizer within the chest and having escape without the same, said part without

55 the chest forming a generator, and a condenser-absorber associated with the latter and having a signal.

60 6. The combination of an ice chest having an opening, a swinging closure therefor movable in a vertical path, rocking refrigerating

means carried by and movable with the closure with one part normally within and another part without the chest and the within part movable through the opening for the closure, a cooling liquid lead between the parts, means for circulating liquid about the part normally within the chest, and a temperature stabilizer within the chest and having escape without the same, said part without the chest forming a generator, a condenser-absorber associated with the latter and having a signal, and a refrigerant within the part normally within the chest.

70 In testimony whereof I affix my signature.
